The ornamental design for a pipeline bracket, as shown and described.

DESCRIPTION

FIG. 1 is a top perspective view of a pipeline bracket showing our new design thereof;

FIG. 2 is a side view of the pipeline bracket shown in FIG. 1; FIG. 3 is a top view of the pipeline bracket shown in FIG. 1; FIG. 4 is a front view of the pipeline bracket shown in FIG. 1; and,

FIG. 5 is a perspective view of the pipeline bracket, with environmental structures, shown in FIG. 1.

Elements shown in broken lines depict portions of the pipeline bracket that form no part of our design.

1 Claim, 5 Drawing Sheets**FIG. 1**
